CLAIM

The ornamental design for a battery, as shown and described.

DESCRIPTION

FIG. 1 is a front right perspective view of a battery.

FIG. 2 is a rear view of the battery of FIG. 1.

FIG. 3 is a front view of the battery of FIG. 1.

FIG. 4 is a right side view of the battery of FIG. 1.

FIG. 5 is a left side view of the battery of FIG. 1.

FIG. 6 is a top plan view of the battery of FIG. 1; and,

FIG. 7 is a bottom plan view of the battery of FIG. 1.

The broken lines in the drawings are for the purpose of illustrating portions of the article that form no part of the claimed design.

1 Claim, 7 Drawing Sheets
